NARROW FOLDABLE BRIDGE

Alfredo Heidenreich, Buenos Aires, Argentina

Application April 8, 1940, Serial No. 328,474
In Argentina March 1, 1940

7 Claims. (Cl. 14—45)

This invention relates to a narrow foldable bridge to be used at places where either a natural or an artificial obstacle would hinder individuals, animals or things from crossing, and particularly to be used for passing over unstable surfaces, ravines, channels, excavations, etc., such as limited extensions of water, swamps, sandy grounds, snow, morasses, etc.

More particularly the invention has for its object a narrow bridge permitting the crossing of a river, channel, brook or lake in a manner such as is afforded by a military pontoon bridge.

The invention comprises, essentially, a series of girders suitably interconnected by a joint link in such a way as to space them parallelly apart for a limited space in their unfolded condition and, vice versa, to hold them together in their folded condition. A series of plates is hingedly and successively arranged between the said girders to cooperate with these in forming a surface or floor to be used as a pathway. In folding the narrow bridge these plates are lifted thereby permitting the girders to be juxtaposed and reducing the bulk of the object to a minimum. In this manner the conveyance, storage and quick erection of the bridge at any desired place is facilitated.

When this bridge is laid over an extension of water and reasons of stability would make it necessary for the same to be supported at intermediate points, the same may be laid over rafts, pontoons, floating bodies or other equivalent means capable of supporting the same on said liquid. In the case of shallow waters or inundated plots of land, other kinds of supports such as posts, piles, abutments, piers, sleepers, etc., may be employed for the same purpose.

In order that the invention may be easily put into practice it is shown by way of example in the accompanying drawings wherein:

Fig. 1 is a fragmentary side view in section along the line I—J of Fig. 2 of one type of bridge the girders of which have for their joint link a series of arms arranged in a scissor-like manner, the bridge being shown in its unfolded condition;

Fig. 2 is a plan view of the bridge described in the foregoing figure;

Fig. 2a is a schematic plan view showing the joint link of this type of bridge;

Fig. 3 is a side view of the same bridge in its folded condition;

Fig. 4 is a detail sectional view along A—B of Fig. 2 on an enlarged scale;

Fig. 5 is a longitudinal section along the line C—D of Fig. 2.

The construction according to the model illustrated in Figs. 1 to 5 consists of the girders 1 each of which is composed of two similar elements spaced apart by means of the spacers 2. Spaces 2' are formed between the elements.

To the upper edges of the girders 1 formed and arranged in the same order as these there are secured the plates 3 by means of the hinges 4 so as to allow them to swing over the upper portion, as may be seen from Figs. 1 and 3. The width of these plates 3 should be such as to permit the plates to fill the gap between each successive pair of girders when the apparatus is unfolded. The said plates 3 may have their ends provided with extensions forming a sort of wing (as indicated by 3' in Fig. 2) adapted to remain extended or be turned about hinges.

To the first and the last girder 1' of the series there are hingedly secured, one in the same manner as the other, the plates 3a which constitute the approach ramps of the bridge and may eventually serve as the walls of a box to enclose the apparatus in its folded condition, as may be inferred from Fig. 3.

25 In the type of bridge illustrated in Figs. 1 to 5 inclusive, the girders 1 are interconnected by two sets of pivoted arms 5—5a operating in the spaces 2'. The arms of each set are so pivoted to each other and to the girders as to function in the manner of lazy tongs, as shown in Fig. 2. For example, successive girders may be interconnected by two pairs of intersecting arms 5—5a, as shown in Fig. 2a. The arms of each pair are pivoted together at their point of intersection, as shown at 6. The outer end of each of the intersecting arms is pivoted to one of the girders by means of a fixed pivot, as shown at 6a. The inner end of each of the intersecting arms pivots around a pin 6b which slides at its ends in slots 7 provided in the upper and lower elements of the girder (see also Fig. 4). On each girder (except the end ones) two arms will, of course, be pivoted at 6a and two arms will be pivoted at 6b, as shown in Figs. 2 and 5. Thus it will be seen that the pivoted arms forming the two lazy tongs are extensible in a horizontal plane which is parallel to the upper plane of the girders.

40 A chain 8 extends along the side of the bridge and is connected to each of the plates 3 near that end of the plate which is remote from the hinge 4.

45 A slide 5b is attached to the underside of two successive girders at any point where it is desired to reinforce the bridge. Each slide has an elongated slot 5c. One end of the slide may be fastened to the underside of one girder by a pin 6d,

and a pin 6c on an adjacent girder engages in the slot 5c and assists in holding the slide in place. These slides do not interfere with the folding and unfolding of the bridge but they serve to limit its extensibility.

In using the narrow bridge over an extension of water a series of floating bodies *a* (Fig. 1) is arranged thereunder at suitable intervals. The girders 1 will simply rest on or be suitably secured to these floating bodies, as the case may be, so as to assure the stability of the apparatus on the surface of the water and cause the same to stand the loads passing over the same. The floating bodies may be applied also under the wings 3' (Fig. 2) in order to impart the apparatus a greater floating capacity.

If so demanded by the circumstances, one or more of the apparatuses described may be used, either one by the side of the other, or one following the other, or both arrangements combined in one, this depending on the length and the width it is desired to impart the path-way constituted by these means.

To immobilize and confine the narrow bridges during their use they are moored by means of cables, ropes, anchors, etc.

In order to make the use of the apparatus safer this may be provided with railings made of stanchions 9 and ropes 9a (Figs. 1 and 2), in the manner as arranged for on certain vessels. The railings may be made also to form a whole with the narrow bridge to which effect it will be sufficient for the ends of each girder 1 to perpendicularly receive the corresponding uprights which will then be interconnected by means of a system of extensible arms similar to 5 and 5a (Fig. 2a), or by means of cables, ropes, etc.

The operation is as follows:

To fold the apparatus all that is necessary is to lift all of the plates 3 by pulling the chain 8 or by means of a simple manual operation. Thereupon the girders 1 may be brought to a closely adjacent relationship, this being an easy task since the arms 5 interconnecting the same facilitate this operation. As is obvious, the folded apparatus will represent an appreciable reduction of its extension for which reason it may readily be conveyed and stored at any appropriate place. Ties and wrapping material may be used to better bundle it.

As mentioned above, the narrow bridge may be used also in connection with unstable surfaces, such as swamps and morasses, as well as on compressible plots of land or on treacherous ground or on ditch-furrowed tracts of land; in all and any of these cases it will permit the passage of vehicles without exposing them to the danger involved by soils of this nature.

I claim:

1. A narrow foldable bridge comprising a series of substantially horizontally disposed girders arranged in parallel and successive relationship, an extensible series of arms connecting the said girders, said series of arms comprising a pair of crossed arms located between each pair of girders and pivotally connected together where they cross, the ends of the crossed arms being pivotally connected to the girders between which the crossed arms are located and the connections between the ends of the arms and the girders permitting movement of the girders toward and away from each other and allowing relative movement longitudinally of the girder between the ends of the two arms connected to such girder, the said arms of the series being disposed at a level lower

than that of the upper plane of the girders and being extensible in a plane parallel to said upper plane of the girders, and a plate hinged to the upper portion of each of said girders.

5 2. A narrow foldable bridge comprising a series of substantially horizontally disposed girders arranged in parallel and successive relationship, an extensible series of arms connecting the said girders, said series of arms comprising a pair of crossed arms located between each pair of girders and pivotally connected together where they cross, the ends of the crossed arms being pivotally connected to the girders between which the crossed arms are located and the connections between the ends of the arms and the girders permitting movement of the girders toward and away from each other and allowing relative movement longitudinally of the girder between the ends of the two arms connected to such girder, the said arms of the series being disposed at a level lower than that of the upper plane of the girders and being extensible in a plane parallel to said upper plane of the girders, a plate hinged to the upper portion of each of said girders, and plates movably secured to the opposite initial girders of the bridge providing approach ramps.

3. A narrow foldable bridge comprising a series of substantially horizontally disposed girders arranged in parallel and successive relationship, an extensible series of arms connecting the said girders, said series of arms comprising a pair of crossed arms located between each pair of girders and pivotally connected together where they cross, the ends of the crossed arms being pivotally connected to the girders between which the crossed arms are located and the connections between the ends of the arms and the girders permitting movement of the girders toward and away from each other and allowing relative movement longitudinally of the girder between the ends of the two arms connected to such girder, the said arms of the series being disposed at a level lower than that of the upper plane of the girders and being extensible in a plane parallel to said upper plane of the girders, and a plate hinged to the upper portion of each of said girders, all of the said plates being connected to tensioning means secured thereto at a point remote from the hinged connection.

4. A narrow foldable bridge comprising a series of substantially horizontally disposed girders arranged in parallel and successive relationship and provided at a level lower than that of the upper plane of the girders with a series of interconnecting arms having a lazy tongs configuration extensible in a plane parallel to said upper plane of the girders and on an axis perpendicular to the axis of each of the said girders, said series of arms comprising a pair of crossed arms located between each pair of girders and pivotally connected together where they cross, the ends of the crossed arms being pivotally connected to the girders between which the crossed arms are located and the connections between the ends of the arms and the girders permitting movement of the girders toward and away from each other and allowing relative movement longitudinally of the girder between the ends of the two arms connected to such girder and a plate hinged to the upper portion of each of said girders.

5. A narrow foldable bridge comprising a series of substantially horizontally disposed girders arranged in parallel and successive relationship and provided at a level lower than that of the upper plane of the girders with a series of interconnecting arms having a lazy tongs configura-

tion extensible in a plane parallel to said upper plane of the girders and on an axis perpendicular to the axis of each of the said girders, said series of arms comprising a pair of crossed arms located between each pair of girders and pivotally connected together where they cross, the ends of the crossed arms being pivotally connected to the girders between which the crossed arms are located and the connections between the ends of the arms and the girders permitting movement of the girders toward and away from each other and allowing relative movement longitudinally of the girder between the ends of the two arms connected to such girder, each of the said girders being composed of two superposed spaced but connected members, the space between said members serving as the housing for the ends of the said interconnecting arms, and a plate hinged to the upper member of each of said girders.

6. A narrow foldable bridge comprising a series of substantially horizontally disposed girders arranged in parallel and successive relationship and provided at a level lower than that of the upper plane of the girders with a series of interconnecting arms having a lazy tongs configuration extensible in a plane parallel to said upper plane of the girders and on an axis perpendicular to the axis of each of the said girders, said series of arms comprising a pair of crossed arms located between each pair of girders and pivotally connected together where they cross, the ends of the crossed arms being pivotally connected to the girders between which the crossed arms are located and the connections between the ends of

the arms and the girders permitting movement of the girders toward and away from each other and allowing relative movement longitudinally of the girder between the ends of the two arms connected to such girder, reenforcing elongated plates connecting at least one pair of adjacent girders secured at one end to one of the said pair of girders and slidably secured to the other of said pair, and a plate hinged to the upper portion 10 of each of said girders.

7. A narrow foldable bridge comprising a series of substantially horizontally disposed girders arranged in parallel and successive relationship, a series of connecting arms having a lazy tongs 15 configuration connecting said girders, said series of arms comprising a pair of crossed arms located between each pair of girders and pivotally connected together where they cross, the ends of the crossed arms being pivotally connected to the girders between which the crossed arms are located and the connections between the ends of the arms and the girders permitting movement of the girders toward and away from each other and allowing relative movement 20 longitudinally of the girder between the ends of the two arms connected to such girder, said arms of the series being extensible in a horizontal plane, a plate hinged to the upper portion of each of said girders, and a railing mounted on said girders and comprising rigid uprights mounted 25 on the girders and a flexible cable connecting the upper ends of the uprights.

ALFREDO HEIDENREICH.
